UNITED STATES PATENT OFFICE.

EDWIN O. WILLIAMS, OF TAUNTON, MASSACHUSETTS, ASSIGNOR TO HIMSELF
AND BYRON L. DWINELL, OF SAME PLACE.

DRILL-MAKING MACHINE.

SPECIFICATION forming part of Letters Patent No. 293,292, dated February 12, 1884.

Application filed June 22, 1883. (No model.)

To all whom it may concern:

Be it known that I, EDWIN O. WILLIAMS, a citizen of the United States, residing at Taunton, in the county of Bristol and State of Massachusetts, have invented certain Improvements in Drill-Making Machines, of which the following is a full, clear, and exact description, reference being had to the accompanying drawings, making part of this specification, in which—

Figure 1 is a plan of a forging-machine constructed in accordance with my invention. Fig. 2 is an elevation of one side of the same. Fig. 3 is a vertical section through the center of the same. Fig. 4 is a horizontal section through the same, taken in a plane passing through the side rocking levers. Fig. 5 is a transverse vertical section through the same enlarged, taken in a plane passing through the centers of the four rocking levers which carry the dies, showing a grooved drill between the latter. Fig. 6 is an enlarged perspective view of one of the vertical rocking levers detached. Fig. 7 is an enlarged perspective view of one of the side rocking levers detached.

My invention relates particularly to forging-machines for rolling grooved or fluted drills, and has for its object to enable me to effect this operation in a much more perfect manner than has hitherto been possible. Heretofore it has been customary to produce the grooves in forged fluted or grooved drills by passing the rod or blank a number of times between a single pair of rolls provided with suitable dies; but as these dies operate from two opposite sides only of the blank—*i. e.*, the sides in which the grooves are formed—the metal at the bottom of the grooves is compressed or drawn down to a greater extent than the thicker portion of the metal at the upper edges of the grooves, which is stretched in such manner as to cause it to frequently crack along the outer edges of these grooves. Furthermore, the edges of the grooves are not rendered sharp, as required, but are rounded by the action of the dies, which press the metal inward at these points. Moreover, a portion of the metal is always forced out between the

dies, producing longitudinal fins, which must be rolled down smooth by changing from one pair of dies to another and turning the rod or blank a quarter-way round at each change, and this alternate rolling of the drill first upon two opposite sides to produce the grooves and then upon the two other opposite sides to roll down the fins often causes the metal at the center of the bottom of the grooves, where it is thinnest, to crack or split longitudinally, which spoils the drill being forged and renders it valueless.

My invention has for its object to overcome these difficulties; and it consists in a forging-machine provided with four rocking levers, each having a suitable die, and adapted to operate simultaneously upon four opposite sides of the drill-blank or other article being forged, whereby the grooves are produced in a perfect manner with sharp edges, as desired, and without the formation of fins upon the metal, and all liability of cracking or splitting the metal in the operation, as heretofore, entirely avoided; and my invention also consists in certain details of construction, as will be hereinafter set forth and specifically claimed.

In the said drawings, A represents the bed or frame of the machine, which is supported on suitable legs, as shown.

B C D E are four levers, arranged in pairs, the journals of the two horizontal or side levers B C having stationary bearings in the bed A, and the journals of the two vertical levers D E having their bearings in two levers or carriers, G H, which are pivoted at or near their centers between lugs b, projecting from the upper and under surfaces of the bed A. The vertical levers D E are provided with convex dies c, adapted to form grooves in two opposite sides of the rod or drill blank, and the horizontal levers B C are furnished with concave dies d, formed to fit around the two opposite or ungrooved sides of the rod, and, with the dies c, inclose the rod around its entire circumference, as seen in Fig. 5.

To the outer ends of the levers D E are pivoted connecting-rods e e, which are pivoted to cranks g h on short shafts i k, having their bearings in brackets I, these shafts i k hav-

ing secured to their outer ends gears K L, which are driven by a gear, M, secured to a horizontal shaft, N, which runs in bearings on the bed A. To the opposite ends of this shaft N are secured two cranks, l m, which are connected by rods n p with a cross-head, P, which slides backward and forward within a suitable space or guideway, 10, formed within the bed A, and to the opposite ends of the cross-head are pivoted two connecting-rods, Q Q, the opposite ends of which are pivoted to the outer extremities of the side levers, B C. The gear M engages with a gear, R, on the driving-shaft S, and thus as the latter is rotated the four die-levers B C D E, through the connections described, are simultaneously rocked or vibrated on their pivots in such manner as to cause the rod or drill blank, when entered between the four dies, to be drawn 20 inward and again forced outward for the purpose of rolling the grooves. As the grooves cannot be properly formed at a single operation of the rocking die-levers, the rod or drill blank must be introduced between and subjected to the action of the dies a number of times in order to gradually roll the grooves down to the desired depth; and to effect this result without the necessity of employing a series of dies arranged at varying distances 30 apart, the vertical die-levers D E, instead of having their journals in stationary bearings, are pivoted within the levers or carriers G H, as previously described, and the front ends of these carriers are caused to approach each 35 other at each inward vibration of the die-levers, in order to diminish the distance between the convex grooving-dies c, in the following manner: Within a rectangular aperture in the bed A is placed, between the rear ends of the 40 carriers G H, a cam, T, which is secured to a horizontal shaft, q, having its bearings in the bed A. This cam is provided with two projections, 12 13, one for each of the carrier-levers G H, whereby as the cam is rotated the 45 rear ends of the levers are gradually separated from each other against the resistance of springs r r, thus diminishing the distance between the dies c, as required. The cam T is rotated intermittently to produce a movement 50 of the carrier-levers G H at each forward movement of the outer ends of the die-levers by means of a ratchet-wheel, t, which is secured to one end of the shaft q and actuated by a spring pawl or arm, u, secured to the 55 cross-head P, the ratchet-wheel being moved a distance equal to that between two of its short teeth at each forward movement of the cross-head. The ratchet-wheel t is provided with ten teeth and two flattened portions or 60 spaces, a', on opposite sides, and when one of these spaces a' is brought uppermost the pawl u will move thereover without turning the ratchet-wheel, the intermittent rotation of which is thus automatically stopped after the 65 rod has been rolled the required number of times, until it is moved forward by means of

a hand-lever, b', provided with a pawl, c', and spring d' sufficiently to cause the pawl u to engage with the first tooth beyond the space a' on the next forward traverse of the cross-head, 70 the hand-lever being moved just before a new rod or blank is inserted between the dies. Instead, however, of the hand-lever b', with its pawl, a simple crank-handle or other device may be used for turning the ratchet-wheel. The number of teeth between the two spaces a' on each side of the ratchet-wheel t corresponds to the number of times that the rod or drill-blank is to be subjected to the action of the rocking dies. Five times has been found 80 to answer well; but the number of times may be varied as desired by increasing or diminishing the number of teeth on each half of the ratchet-wheel t. The spaces a' of the wheel t are successively brought into line with the 85 path of the pawl u immediately after the cam T has been rotated into a position to allow the carrier-levers G H to be separated at their front ends to their greatest extent by their springs r r, and by thus automatically preventing a further rotation of the ratchet-wheel at this time the dies c are always left at their greatest distance apart after a drill has been forged, and caused to remain in such position until a new blank is inserted, when the ratchet-wheel is again brought into action by a movement of the auxiliary lever b', as before described, when the dies c will be advanced or brought nearer and nearer together until the 90 operation of rolling the blank is completed. 100 It will be apparent that as the driving-shaft is rotated continuously, if the rotation of the cam T was not automatically arrested at the proper time, the blank might be inserted when the dies c were nearest together, or in a relative 105 position other than the proper one for the commencement of the rolling operation, hence the necessity of employing an automatic device for insuring the dies being in the proper position at the commencement of the work. 110

Instead of having the journals of the horizontal or side levers, B C, supported in stationary bearings, as shown and described, they may have their bearings in levers or carriers of similar construction to those G H of the vertical levers, and operated in like manner to cause the dies of the levers B C to advance toward and recede from each other, which construction would be found desirable for rolling 115 an article with four longitudinal grooves in its four opposite sides. 120

Although the above-described machine is intended particularly for rolling fluted or ground drills, it is evident that it may be employed for rolling other articles, if desired, it 125 being merely necessary to employ dies of the proper form to give the article being rolled the desired shape in cross-section.

The above-described machine possesses great advantages over those heretofore constructed, 130 having a single pair of dies working upon two sides of the rod or blank, as the four dies of

my machine operating simultaneously upon all sides of the rod and extending around its entire circumference serve to draw down the metal equally at all points at the same time and avoid the necessity of alternately rolling the blank between different pairs of dies, first upon two opposite sides and then upon the two other opposite sides, whereby the stretching and cracking or splitting of the metal and the formation of fins is avoided, and the corners or edges of the grooves rendered sharp and perfect, as desired, desiderata hitherto unattained in any machines for forging grooved drills with which I am acquainted.

15 What I claim as my invention, and desire to secure by Letters Patent, is—

1. In a forging-machine, the combination of four rocking levers arranged in opposite pairs, and provided with convex and concave dies, 20 respectively, said dies adapted to operate simultaneously upon the four opposite sides of a drill-blank or other piece of metal, and to extend entirely around the same, and means for operating said levers, the grooves in the 25 blank being rolled as the blank is drawn in and forced out between the dies, substantially as and for the purpose set forth.

2. In a forging-machine, the combination of a pair of rocking levers provided with dies 30 adapted to produce longitudinal grooves in two opposite sides of a rod or drill blank, with a pair of rocking levers provided with dies adapted to operate simultaneously with the grooving-dies upon the outside of the rod 35 or drill blank between the edges of the grooves, means for diminishing the distance between the grooving-dies, and means for operating said levers, substantially in the manner and for the purpose set forth.

3. In a forging-machine, the combination, 40 with a pair of rocking levers provided with dies, and adapted to operate upon two opposite sides of a rod or drill blank, of a pair of levers, D E, provided with dies, and pivoted to levers or carriers G H, and means, substantially as described, for operating said carriers to cause the dies of their levers D E to advance toward and recede from each other, substantially as and for the purpose set forth.

4. In a forging-machine, the combination, 50 with the movable carriers G H and their rocking levers D E, provided with dies, of the cam T, placed between the carriers G H, the springs r r, shaft q, ratchet-wheel t, and the arm or pawl u, all constructed to operate substantially in the manner and for the purpose described.

5. In a forging-machine, the combination of the movable carriers G H, the rocking levers D E, pivoted thereto and provided with dies, 60 the cam T, shaft q, pawl u, and the ratchet-wheel t, secured to the cam-shaft, and provided with one or more spaces, a', whereby the intermittent rotation of the cam T is automatically arrested when the rod or blank has been 65 rolled the required number of times, and the dies c have been separated to their greatest distance apart, all constructed to operate substantially in the manner and for the purpose set forth.

70 Witness my hand this 18th day of June,
A. D. 1883.

EDWIN O. WILLIAMS.
